UNITED STATES PATENT OFFICE.

DE FORREST CHAMPEON, OF HOULTON, MAINE.

TELEPHONE-SIGNAL.

1,177,485.

Specification of Letters Patent. Patented Mar. 28, 1916.

Application filed September 16, 1914. Serial No. 862,064.

To all whom it may concern:

Be it known that I, DE FORREST CHAMPEON, a citizen of the United States, residing at Houlton, in the county of Aroostook and State of Maine, have invented new and useful Improvements in Telephone-Signals, of which the following is a specification.

This invention relates to improvements in 10 signaling devices for telephones and has particular application to an automatic local signal.

In carrying out the present invention, it is my purpose to provide an automatic local 15 signal for telephone sets which will be found especially useful on party lines whereby the calling and called subscribers will be advised when a third party listens in.

It is also my purpose to provide an audible 20 signal of the class described which will be located in the transmitter of the telephone set and controlled by the receiver arm so that when the latter is relieved of the weight of the receiver and moves upwardly, 25 incident to the removal of the receiver therefrom, the signal in the transmitter will be actuated and the sound waves therefrom sent over the transmission line, the latter having been previously closed by the upward 30 movement of the receiver arm.

A further object of my invention is to provide a signaling device of the type set forth which will embrace the desired features of simplicity, efficiency and durability, 35 which may be installed and maintained at a minimum expense and which will operate effectively under all conditions and whereby the central exchange operator of a party line telephone system will be advised audibly of 40 the particular calling subscriber.

With the above and other objects in view, the invention consists in the construction, combination and arrangement of parts hereinafter set forth in and falling within the 45 scope of the claims.

In the accompanying drawings; Figure 1 is a diagrammatic sectional view of a signaling device constructed in accordance with the present invention and installed in a telephone set. Fig. 2 is a cross sectional view on the line 2—2 of Fig. 1. Fig. 3 is a similar view on the line 3—3 of Fig. 1. Fig. 4 is a perspective view of a detail of the invention. Fig. 5 is a sectional view through the transmitter showing the audible signal carried

thereby. Fig. 6 is a view in edge elevation of the audible signal removed from the transmitter.

In the drawings, I have shown a telephone set comprising the usual standard 1, receiver 2 and transmitter 3. Formed in the standard 1 at an appropriate point is a vertical slot 4 and projecting through the slot 4 and capable of vertical movement therein is an arm 5 having the outer end thereof formed to provide a fork 6 designed to hold the receiver 2 and the inner end thereof connected with a vertical rod 7 slidably mounted within vertically alining openings formed in superposed supporting brackets 8, 8. Secured to the under surface of each supporting bracket adjacent to the opposite ends of the opening therein are rollers 9 bearing against the adjacent edges of the rod 7 so as to eliminate friction between the rod and the end walls of the openings. Extending upwardly from the top bracket 8 is an arm 10 having the upper end thereof bent at right angles to itself and lying in a plane parallel with the bracket 8. Depending from the right angular portion 11 of the arm 10 is a spring jack 12 connected in the transmission circuit, while on the upper extremity of the rod 7 and insulated therefrom is a plug 13 adapted to enter the jack 12 and close the transmission circuit. A coiled contractile spring 14 has one end fastened to the under surface of the upper bracket 8 and the lower end secured to the arm 5 carrying the receiver and, upon the removal of the receiver from the hook 6, the spring 14 reacts and slides the rod 7 upwardly thereby engaging the plug 13 with the jack 12 so as to close the transmission circuit whereby conversation may be carried on through the transmitter 3 and receiver 2.

Projecting upwardly from the lower bracket 8 parallel with the rod 7 is an arm 15 carrying a plate formed of alternate sections of conducting material 17 and insulating material 18, the sections of conducting material being connected to one another by means of a common strip 19, while the sections of insulating material are similarly connected by a common strip 20. The upper end of the arm 15 is bent at right angles to itself as at 21, such bent portion lies in a plane parallel with the lower bracket 8 and formed in the right angular portion 21 of the arm 15 and the bracket 8 are alining openings in which

is mounted for sliding movement a shank 22 having the lower end thereof connected with the piston of a dash pot 23 and the upper end formed with an eye 24 to which is fastened one extremity of a coiled contractile spring 25, such spring having the opposite end thereof secured to a bracket 26 carried by the arm 10. Fixed to the shank 22 and projecting outwardly therefrom at right angles thereto is a contact finger 27 adapted to wipe over the plate 16 and normally disposed at the lower end of such plate. In order to hold the shank 22 in lowered position against the action of the spring 25 a suitable form of catch is provided. In the present instance, a dog 28 is pivoted upon the right angular portion 21 of the arm 15 and normally engages a depression 29 formed in the adjacent portion of the shank 22, such dog acting to hold the shank against upward sliding movement under the action of the spring 25. Connected with the shank 22 adjacent to the point of connection of the contact finger 27 and projecting outwardly from such shank in a direction opposite from the contact finger is a lug 30, while formed on the rod 7 and normally engaging the lug 30 is a lug 31, while connected with the rod 7 above the lug 31 is a finger 32 designed to engage the dog 28 and hold the latter normally the depression 29.

Under normal conditions, that is, when the telephone set is out of service, the rod 7 and shank 22 are in lowered positions and held in such positions against the action of the springs 14 and 25 respectively. When the arm 5 is relieved of the weight of the receiver 2 the spring 14 reacts and so slides the rod 7 upwardly thereby engaging the plug 13 with the jack 12 and closing the transmission circuit. In the upward movement of the rod 7 the finger 32 disengages the dog 28 and the lug 31 disengages the lug 30 and contacts with the dog 28 simultaneously with the plug 13 entering the jack 12. As the lug 31 engages the dog 28 the latter is swung about its pivotal connection with the right angular portion 21 of the arm 15 and moved out of the recess or depression 29 in the shank 22 thereby releasing the latter. Upon the release of the shank 22 the spring 25 reacts and slides the shank upwardly whereby the finger 27 rides over the plate 16 and engages the conducting sections 17 successively or one after the other. As the shank moves upwardly under the action of the spring 25 the dash pot 23 retards the motion of the shank so that the contact finger 27 will ride into and out of engagement with the successive conducting sections 16 slowly and in an even and uniform manner. When the receiver is replaced on the fork 6 the weight of such receiver slides the rod 7 downwardly against the action of the spring 14 and in the downward movement of the

rod 7 the lug 31 in engagement with the lug 30 on the shank 31 restores the latter to normal position, the shank sliding downwardly rapidly under the weight of the receiver.

34 designates an audible signal which, in the present instance, is in the form of an interrupter disposed within a casing 35 having one side adjacent to one end thereof formed with an interiorly threaded socket 36 and the opposite side formed with an outwardly exteriorly threaded nipple 37 alining axially with the socket 36. The extension on the nipple 37 is threaded into the transmitter casing in advance of the sound transmitting diaphragm, while the mouth piece of the transmitter is threaded into the socket 36. The interrupter 34 is connected in an electric circuit 38 including a suitable source of energy as a battery 39 and having the terminals thereof connected with the contact finger 27 and the common strip 19 respectively. By means of this construction, it will be seen that as the contact finger 27 moves over the conducting sections of the plate 16 in the upward movement of the shank 22, the circuit 38 will be interrupted a certain number of times, corresponding with the number of insulated sections 18, thereby energizing the audible signal 33 in the transmitter and deenergizing such signal in accordance with the making and breaking of the circuit under the action of the finger 27 and plate 16. As the signal 34 is operated after the transmission circuit is closed, the sound waves set up by such signal are transmitted to the central station and as the number, or arrangement, or both, of the segments of the plate 16 of each station differs from the segments on the plates at every other station, the operator will be advised as to the particular calling station. It is to be understood that the contact plate and insulating block designated by the reference numerals 17, 18, 19 and 20 are made integral with one another and are removable and interchangeable to facilitate the changing of the signal when desired. When the called subscriber removes the receiver from the arm the mechanism controlled by such arm is actuated as previously described and the local audible signal 33 actuated a number of times corresponding with the number of conducting segments on the plate so that the sound waves are transmitted over the transmission line to the calling subscriber's instrument whereby the calling subscriber is notified that the called subscriber is on the line. Should a third party attempt to "listen in" the interrupter or audible signal of such party will operate and thereby advise the parties using the line of the third party's presence.

From the foregoing description taken in connection with the accompanying draw-

ings, the construction, mode of operation and manner of employing my improved signaling device will be readily apparent.

It will be seen that I have provided a 5 signaling device which will be found especially useful in party line telephone systems and whereby two parties using the line will be automatically notified when the third party listens in.

10 While I have herein shown and described one preferred form of my invention by way of illustration, I wish it to be understood that I do not limit or confine myself to the precise details of construction herein described and delineated, as modification and 15 variation may be made within the scope of the claims without departing from the spirit of the invention.

I claim:

20 1. In a telephone signal, the combination with the receiver arm and transmitter, of an electroresponsive audible signal in juxtaposition to said transmitter, a local circuit including said signal, a circuit closer in said 25 circuit constructed to intermittently close and open the circuit a predetermined number of times in the operation of said circuit closer, means holding said circuit closer normally in open position, and means operable 30 from said arm in the movement thereof upon the removal of the receiver and succeeding the closing of the transmission circuit to release said holding means.

2. In a telephone signal, the combination 35 with the receiver arm and transmitter, of an electroresponsive audible signal in juxtaposition to said transmitter, a local circuit including said signal, a circuit closer in said circuit constructed to intermittently close 40 and open the circuit a predetermined number of times in the operation of said circuit closer, means holding said circuit closer normally in open position, means operable from said arm in the movement thereof upon the 45 removal of the receiver and succeeding the closing of the transmission circuit to release said holding means, a spring for actuating said circuit closer upon the release of said holding means, and means for retarding the 50 movement of said circuit closer under the action of said spring.

3. In a telephone signal, the combination 55 with the receiver arm and transmitter, of an electroresponsive audible signal in juxtaposition to said transmitter, a local circuit for said signal, a circuit closer connected in said circuit and comprising alternate sections of insulating material and conducting material, a shank disposed in juxtaposition to 60 said sections and capable of vertical sliding

movement, and a finger on said shank adapted to ride over said sections in the movement of the shank to alternately close and open said local circuit, and means operable upon the removal of the receiver hook from 65 said arm to slide said shank.

4. In a telephone signal, the combination 70 with the receiver arm and transmitter, of an electroresponsive audible signal in juxtaposition to said transmitter, a local circuit for said signal, a circuit closer connected in said circuit and comprising alternate sections of insulating material and conducting material, a shank disposed in juxtaposition to said sections and capable of vertical sliding 75 movement, means holding said shank normally in lowered position and operable upon the removal of the receiver from said arm to release said shank, and means for sliding said shank upon the release thereof. 80

5. In a telephone signal, the combination 85 with the receiver arm and transmitter, of an electroresponsive audible signal in juxtaposition to said transmitter, a local circuit for said signal, a circuit closer connected in said circuit and comprising alternate sections of insulating material and conducting material, a shank disposed in juxtaposition to said sections and capable of vertical sliding movement, means holding said shank 90 normally in lowered position and operable upon the removal of the receiver from said arm to release said shank, means for sliding said shank upon the release thereof, and means operable upon the restoring of the 95 receiver upon said arm to restore said shank to normal position.

6. In a telephone signal, the combination 100 with the receiver arm and transmitter, of an electroresponsive audible signal in juxtaposition to said transmitter, a local circuit for said signal, a circuit closer connected in said circuit and comprising alternate sections of insulating material and conducting material, a shank disposed in juxtaposition to 105 said sections and capable of vertical sliding movement, means holding said shank normally in lowered position and operable upon the removal of the receiver from said arm to release said shank, means for sliding said 110 shank upon the release thereof, and means for retarding the movement of said shank under the action of the operating means thereof.

In testimony whereof I affix my signature 115 in presence of two witnesses.

DE FORREST CHAMPEON.
